UNITED STATES PATENT OFFICE.

CHARLES EDMUND KELLS, OF NEW ORLEANS, LOUISIANA.

ROTARY COMPRESSOR.

1,211,169.

Specification of Letters Patent.

Patented Jan. 2, 1917.

Application filed April 10, 1916. Serial No. 90,200.

To all whom it may concern:

Be it known that I, CHARLES EDMUND KELLS, a citizen of the United States, residing in New Orleans, in the parish of Orleans and State of Louisiana, have invented certain new and useful Improvements in Rotary Compressors, of which the following is a specification.

This invention relates particularly to rotary compressors of the kind employed for compressing air but which are adapted to compress other fluids. Apparatus of this kind is also capable of being employed as a pump or rotary engine, and it will therefore be understood that when I describe my improvements as being embodied in an air compressor I do not intend to be confined in my claims to such apparatus.

It is important that apparatus of this kind should be properly lubricated in order to reduce friction and consequent heat. It is also important that when the apparatus is rotated at high speed and for a prolonged period the heat unavoidably developed should be dissipated and it is also desirable that the noise usually produced should be, as far as possible, eliminated.

The object of my invention is to provide apparatus possessing these characteristics.

In carrying out my invention I provide a rotor and a rotor chamber which may be conveniently located at one end of an electric motor, to the shaft of which the rotor is keyed. The rotor is preferably cylindrical or circular in vertical section and its axis of rotation coincides with the axis of the motor shaft. The rotor chamber is of a general circular shape but is somewhat larger in diameter than the rotor and is eccentric with reference thereto, its lower wall being at all times in contact with the lower portion of the rotor while its upper wall is separated therefrom, thus providing a chamber for the entrance of air and in which the air is compressed. The rotor chamber is so formed that it provides a depressed abutment for the rotor which latter is equipped with vanes which instead of being radially movable, as is often the case, are mounted to swing in recesses in the rotor, being pressed in one direction by springs and being free to move to a sufficient extent in the opposite direction against the pressure of said springs. By a very simple arrangement the vanes while turning about fixed axes are not connected to the

rotor by pivot pins but are loosely mounted in the recesses in the rotor and can be easily inserted or withdrawn when required.

In order to lubricate, I introduce oil or other suitable material near the axis of the rotor and I provide a channel which conveys the lubricant radially to the middle portion of the depressed abutment whereby oil is supplied to the vanes and also to the sides and periphery of the rotor. In order to cool the compressor I may provide the rotor casing with projections or ribs for radiating heat, and I may also attach to the motor shaft a fan which by directing air currents against the rotor casing cools it to some extent.

In order to reduce or eliminate noise I employ an outlet or exhaust opening of small area. This I have demonstrated has the desired effect although it tends to increase heat in the rotor which, however, is compensated by the cooling devices before described.

In the accompanying drawings:—Figure 1 is an end elevation of an electric motor and a compressor, made in accordance with my invention, applied thereto. Fig. 2 is a side elevation thereof with some parts broken away. Fig. 3 is a view similar to Fig. 1 but with the end plate of the rotor removed. Fig. 4 is a perspective view of the rotor. Fig. 5 shows a vertical central section through the rotor, the section being taken at right angles to the axis of the rotor. Fig. 6 is a perspective view of the end plate of the rotor detached, and it shows by dotted lines its relation with the rotor. Fig. 7 is a detail view in section showing the end plate of the rotor and the inlet and outlet ports. Fig. 8 is a diagram illustrating the relation of the rotor with the walls of the rotor chamber, the rotor being circular as shown with its central axis at x , while the walls of the rotor chamber are made up of a series of arcs, some of which are struck from the center x , others from the center y , and others from the center z .

The compressor may be driven in any suitable way, but preferably I employ for this purpose an electric motor A which may be of any suitable kind. The armature shaft B is mounted in suitable bearings which may be lubricated in the manner indicated at C. The motor casing is provided with ventilating openings D, D' and the shaft B carries a fan E which directs air

currents against the motor casing next to the rotor. The rotor casing F may, if desired, be formed in one piece with the head plate of the motor casing and it is provided with 5 ribs or projections f to radiate heat. The rotor casing is closed by a head or end plate G which may be secured to the casing F by screws or bolts g and it is provided with an admission port H and an exit port I, the 10 latter being restricted at i as indicated in Fig. 7.

The rotor L is cylindrical or circular in vertical section. It is keyed to the shaft B and its axis is concentric therewith. It 15 is formed with recesses l of general triangular shape, adapted to receive the vanes M, the inner ends of which are rounded, and are seated in the correspondingly shaped inner portions of the recesses. Each 20 vane is pressed in one direction by a spring n pressing on a plunger pin o, the outer end of which enters a recess p in the adjacent side of the vane. The arrangement is such that the outer ends of the vanes which are 25 beveled or inclined and rounded as shown, are pressed against the wall of the rotor chamber, in the manner clearly indicated in Figs. 3 and 5. It will be observed that the outer end of each vane is so shaped as 30 to make close contact with the wall of the rotor chamber at all times, whether it be pressed outward, as indicated in full lines Fig. 5, or whether it be moved inward, as indicated in the same figure. Preferably 35 only two vanes are employed and they are loosely mounted in the recesses l. While in use they press closely on the inner peripheral wall of the rotor casing or chamber and their sides fit closely the side walls 40 of said chamber. The pins o are loosely connected with the vanes so that the latter may be easily withdrawn and removed when desired. It will furthermore be observed that the recesses which contain the 45 springs n may be easily drilled as the recesses l are so formed that this may be readily accomplished.

It will be observed that while the rotor is truly cylindrical and its action is 50 concentric with that of the motor shaft the rotor chamber, while of a general circular shape, is of somewhat larger diameter than the rotor and is not truly circular. By reference to Fig. 8 it will be seen that the 55 periphery of the rotor coincides with a circle struck from the center x. The upper portion of the rotor chamber above the line r, r coincides with an arc struck from the center y. Those portions of the rotor chamber 60 below the line r and extending to the points s coincide with arcs struck from the center z, the lower portion of the chamber between the points s coinciding with an arc struck from the center x which is the center of rotation of the rotor. In this way 65

a depressed or extended abutment is provided for the rotor between the admission and exhaust ports which efficiently prevents air from passing from the admission side to the exhaust side of the apparatus except 70 by way of the crescent-shaped chamber T above the abutment. In like manner it prevents compressed air from passing to the admission side, compelling it to pass out through the exhaust. 75

In order to lubricate the rotor and its chamber I provide an oil reservoir P on the head plate G which is provided with an adjustable closure p' and delivers through an opening q to the rotor chamber, the lubricant being passed by means of a radial channel q' to the depressed abutment and advisedly to the middle portion thereof. Preferably but not necessarily the channel is formed in the head plate G. In this way 80 the lubricant is delivered at the abutment without danger of air escaping through the lubricant chamber. The oil passes into the recesses l and lubricates the vanes and it also passes through said recesses to the opposite side of the rotor and lubricates its side walls. Much difficulty has heretofore 85 been encountered in properly lubricating rotary compressors of the kind to which my invention relates, but the lubricating devices just described have proved to be most 90 efficient. 95

My improvements are especially applicable to small air compressors or compressors for gases and vapors of various kinds but 100 obviously they are applicable to compressors, pumps, engines, etc., of larger dimensions.

It is quite apparent that I have provided a compressor of very simple construction. 105 I have provided for efficient lubrication, for reduction or elimination of noise, and for dissipation or elimination, to some extent, of heat. I have also provided a compressor in which by very simple devices leakage 110 past the abutment from one port to another is absolutely prevented, and for these reasons the apparatus has by actual demonstration proved to be most efficient in all the tests to which it has been subjected. 115

I claim as my invention:

1. A rotary compressor comprising a rotor chamber having inlet and outlet ports, a rotor within the chamber having V-shaped vane-receiving recesses open at their outer 120 ends and on two opposite sides and swinging vanes loosely mounted in said recesses and removable endwise therefrom and which are pressed inward endwise therein to hold their inner ends seated at all times 125 in the inner ends of said recesses as the rotor revolves.

2. A rotary compressor comprising a rotor chamber having inlet and outlet ports and a curved wall forming an abutment 130

between the inlet and outlet ports, a rotor within said chamber having V-shaped recesses each of which is open at its outer end and on two opposite sides and having 5 one of its closed sides longer than the other, and a swinging vane loosely mounted in each of said recesses which at times projects beyond the periphery of the rotor and at other times lies within the recess, one 10 of the sides of said vane being of the same length as the longer side of the recess and each vane having an inclined outer end fitting the inner peripheral wall of the rotor chamber.

15 3. A rotary compressor comprising a ro-

tor chamber having inlet and outlet ports, and a depressed abutment between the ports, a rotor within the chamber having vane receiving recesses, vanes mounted to swing in said recesses, and a detachable end 20 plate for the rotor chamber provided with a lubricant chamber and with a channel leading radially to the middle portion of the depressed abutment.

In testimony whereof, I have hereunto 25 subscribed my name.

CHARLES EDMUND KELLS.
